UNITED STATES PATENT OFFICE.

MOSES HENRY WILLIAMS, OF FREEHOLD, NEW JERSEY, ASSIGNOR TO A. & M. KARAGHEUSIAN, INC., OF NEW YORK, N. Y., A CORPORATION OF DELAWARE.

DESIGN FOR A RUG.

Application filed March 11, 1924. Serial No. 8,899. Term of patent 7 years.

To all whom it may concern:

Be it known that I, MOSES HENRY WILLIAMS, a citizen of the United States, residing at Freehold, in the county of Monmouth and State of New Jersey, have invented a new, original, and ornamental Design for Rugs, of which the following is a specification, reference being had to the accompanying drawing, forming part thereof.

The figure is a plan view of a rug, showing my new design.

I claim:—

The ornamental design for a rug, substantially as shown.

In testimony whereof I have signed this specification in the presence of two subscribing witnesses.

M. HENRY WILLIAMS.
